US0D1030804S

(12) **United States Design Patent** (10) **Patent No.:** **US D1,030,804 S**
Chen (45) **Date of Patent:** **** Jun. 11, 2024**

(54) **DISPLAY SCREEN OR PORTION THEREOF WITH ICON**

(71) Applicant: **Merry Electronics Co., Ltd.**, Taichung (TW)

(72) Inventor: **I-An Chen**, Taichung (TW)

(73) Assignee: **Merry Electronics Co., Ltd.**, Taichung (TW)

(**) Term: **15 Years**

(21) Appl. No.: **29/839,187**

(22) Filed: **May 19, 2022**

(51) **LOC (14) Cl.** **14-04**

(52) **U.S. Cl.**

USPC **D14/489**

(57) **CLAIM**

The ornamental design for a display screen or portion thereof with icon, as shown and described.

DESCRIPTION

FIG. 1 is a front view of a display screen or portion thereof with icon showing a first embodiment of my new design; and,

FIG. 2 is a front view of a display screen or portion thereof with icon showing a second embodiment of my new design. The dot-dash broken lines illustrate a display screen or portion thereof and form no part of the claimed design. The dashed broken lines illustrate a portion of the icon that form no part of the claimed design.

1 Claim, 2 Drawing Sheets
